US00D633502S

(12) **United States Design Patent**
Alegiani

(10) **Patent No.:** **US D633,502 S**
(45) **Date of Patent:** **** Mar. 1, 2011**

(54) **PORTABLE TERMINAL**

(75) Inventor: **Monica Alegiani, Silvi (IT)**

(73) Assignee: **Datalogic Mobile S.R.L., Lippo di Calderara di Reno (BO)**

(**) Term: **14 Years**

(21) Appl. No.: **29/362,472**

(22) Filed: **May 26, 2010**

CLAIM

I claim the ornamental design for a portable terminal, as shown and described.

DESCRIPTION

FIG. 1 is a perspective front view of a portable terminal according to the present invention.

FIG. 2 is a perspective rear view of the portable terminal of FIG. 1.

FIG. 3 is a front view of the portable terminal of FIG. 1.

FIG. 4 is a rear view of the portable terminal of FIG. 1.

FIG. 5 is a right side view of the portable terminal of FIG. 1.

FIG. 6 is a left side view of the portable terminal of FIG. 1.

FIG. 7 is a top view of the portable terminal of FIG. 1; and,

FIG. 8 is a bottom view of the portable terminal of FIG. 1.

The portions shown in broken line are not claimed.

1 Claim, 6 Drawing Sheets
